UNITED STATES PATENT OFFICE

CHRISTOPHER LEDDER AND OLIN SNOW, OF HARDIN, ILLINOIS

DESIGN FOR A CHAIR

Application filed April 20, 1931. Serial No. 39,578. Term of patent 3½ years.

To all whom it may concern:

Be it known that we, CHRISTOPHER LEDDER and OLIN SNOW, citizens of the United States, residing at Hardin, in the county of Calhoun and State of Illinois, have invented a new, original, and ornamental Design for Chairs, of which the following is a specification, reference being had to the accompanying drawings, forming part thereof.

Fig. 1 is a front perspective view of a chair showing our new design.

Fig. 2 is a rear perspective view.

We claim:

The ornamental design for a chair, as shown.

CHRISTOPHER LEDDER.
OLIN SNOW.
